UNITED STATES PATENT OFFICE

HERBERT A. WALLACE, OF EDGEWOOD, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed July 19, 1928, Serial No. 293,954. Renewed April 2, 1930.

My invention relates to railway traffic controlling apparatus of the type involving switches and signals controlled by any suitable manually operated or manually controlled means such as by the levers of an interlocking machine. More particularly, my present invention relates to means for controlling the polarized indication relay commonly used for the control of switch levers or signal levers, or both, in apparatus of this character.

I will describe two forms of apparatus embodying my invention, and will then point out the novel features thereof in claims.

In the accompanying drawing, Fig. 1 is a diagrammatic view showing one form of apparatus embodying my invention. Fig. 2 is a view showing a modification of a portion of the apparatus shown in Fig. 1 and also embodying my invention.

Similar reference characters refer to similar parts in each of the views.

Referring first to Fig. 1, the reference character S designates a railway switch, and the reference characters C¹, C², C³ and C⁴, designate signals governing traffic over the switch S. Switch S is operated by a switch mechanism D, which in turn is controlled in any suitable manner such as by a switch lever L^s. The signals are similarly controlled in part by means such as a signal lever L^A, through the medium of circuits which will be explained hereinafter. The switch lever L^s may be controlled by an indication relay R in any suitable manner. One form of apparatus for controlling the switch mechanism D by the switch lever L^s, and one form of apparatus for controlling the switch lever by the indication relay R, are illustrated and described in United States Letters Patent No. 1,101,036, granted to B. F. Oler on June 23, 1914. Another form of apparatus for controlling the switch mechanism D by a device other than a lever of an interlocking machine is illustrated and described in United States Letters Patent No. 1,650,575 granted to me on November 22, 1927.

As shown in the drawing, the switch S and the switch lever L^s are in the normal positions. The signal lever L^A is also in its nor-

mal position so that all of the signals indicate "Stop". Relay R is energized in the normal direction, the circuit being from a battery 4 through a pole-changer P, wire 5, winding of relay R, wire 6, contact NB on the lever L^s closed in the normal position and in the normal indicating position, wire 7, normal contact 11-11^a of relay R, wire 8, and pole-changer P to battery 4. The pole-changer P is operated by the switch S in such a manner that when the switch is in the normal position the polarity of the current supplied to relay R is normal, so that the normal contacts 11-11^a and 13-13^a of this relay are closed.

Assuming that the operator desires to reverse the switch S, he first moves the lever L^s to its reverse indicating position, wherein contact NB is open and contact RD is closed. The circuit for relay R is then open at contact NB, and so the neutral contacts of this relay are released, with the result that front contact 12 opens and back contact 10 closes. The normal contacts of the relay, however, do not release until the relay becomes energized by current of reverse polarity. When the switch S moves to its reverse position in response to this operation of the lever L^s, pole-changer P reverses, and a circuit for relay R then becomes closed, which circuit is from battery 4, through pole-changer P, wire 8, back contact 10 of relay R, a resistance 20, the winding of relay R, wire 5, and pole-changer P to battery 4. The current which is thus supplied to relay R is of reverse polarity. The value of resistance 20 is such that the current which then flows through relay R is sufficient to reverse the polarized contacts of the relay, but is not sufficient to operate the neutral contacts. It is a characteristic of polarized relays that the polarized armature will operate on a smaller current than the neutral armature. The reverse contacts of the relay R now being closed, another circuit for this relay is closed, which circuit passes from battery 4, through pole-changer P, wire 8, reverse contact 11-11^b, wire 9, contact RD, wire 6, winding of relay R, wire 5, and pole-changer P to battery 4. The current which then flows

through relay R is of sufficient value to open the back neutral contact 10 and close the front neutral contact 12. The movement of the lever L^s to the full reverse position can now be completed, but this movement does not affect contact RD, and, consequently, does not affect the other parts of the apparatus shown in the drawing.

The operation of the apparatus when the switch S is restored to its normal position will be understood from the foregoing without detailed explanation.

The resistance 20 may be replaced by a low resistance connection if desired, but in that case the neutral contacts of relay R will tend to operate intermittently during the usually short period between the opening of contact NB or RD caused by operation of the lever and the opening of the pole-changer caused by the response of the switch, as well as during the short period between the complete operation of the pole-changer and the response of the polarized armature of the relay. The purpose of resistance 20 is to prevent this intermittent operation of the relay.

Assuming now that relay R is energized in the normal direction, and that the operator swings the signal lever L^A to the left, signal C² will then move to the proceed position, the circuit being from terminal B of a suitable source of current, through normal contact 13—13^a of relay R, wire 14, contact 2—2^b of lever L^A, wire 16, and the operating mechanism of signal C² to terminal O of the same source of current. If the operator swings lever L^A to the right, signal C¹ will be cleared, the circuit for this signal including contact 13—13^a of relay R and contact 2—2^b of lever L^A. When relay R is energized in reverse direction, so that its reverse contact 13—13^b is closed, signal C⁴ will be cleared through contact 3—3^b if lever L^A is swung to the left, and signal C³ will be cleared through contact 3—3^a if the signal lever is swung to the right.

Assuming that all parts of the apparatus are in their normal positions, if the switch lever L^s is moved beyond the normal indication position, relay R will become de-energized due to its normal circuit being open at contact NB and so the circuit for all four signals will be open at front contact 12 of relay R and none of these signals can be cleared. If for any reason the switch S is moved out of the position corresponding to the position of lever L^s, the circuit for relay R will be open at pole-changer P and relay R will be de-energized, with the same result as before. If switch S is moved to the full reverse position while lever L^s remains in the normal position, relay R will become reversely energized reversing the polar contacts but the normal contacts will not be picked up because the current through relay R is less than sufficient to open back contact

10 due to resistance 20 being in series with the relays.

Referring now to Fig. 2, the indication relay which is here designated R^A, is of the alternating current type, having a winding 21 which is supplied with current from a transformer T through the pole-changer P. The primary of transformer T¹ is connected with wires 26 and 27, which are constantly supplied with alternating current from a generator G. Relay R^A comprises a second winding 22, which is constantly connected with the secondary of a transformer T² the primary of which receives energy from wires 26 and 27. Relay R^A comprises three contacts 23^N, 24^N and 25^N, which are operated when the winding 21 is energized by current of normal relative polarity, and three other contacts 23^R, 24^R and 25^R, which are actuated when the winding 21 is energized by current of reverse relative polarity. A relay of this character is illustrated and described in Letters Patent of the United States No. 1,285,498, granted to me on November 19, 1918.

The normal circuit for winding 21 of relay R^A is the same as the circuit for relay R in Fig. 1, and includes contact 24^N, which is closed only when the relay is energized by current of normal relative polarity. The reverse circuit includes contact 24^R, which is closed only when the relay is energized by current of reverse relative polarity. The auxiliary circuit for relay R^A through resistance 20 includes back contacts 23^R and 23^N, both of which are closed when and only when the relay is de-energized or is energized by current flowing through resistance 20. Contacts 24^N and 24^R are adjusted to close when current is of low value due to resistance 20 in the circuit and to remain closed when the current is of full value. Contacts 25^N and 25^R close only when the current is of full value, and contacts 23^N and 23^R open only when the current is of full value. The signal circuits are controlled by normal contact 25^N and reverse contact 25^R in the same way in which these circuits are controlled by the normal and reverse contacts of relay R in Fig. 1.

It is evident that any so-called three-position relay is practically the equivalent of the direct current polarized relay which has been described.

The apparatus shown in Fig. 2 has the same characteristics and advantages as the apparatus shown in Fig. 1.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a railway switch, a lever for the control of said switch, a polarized relay for the control of said lever, a normal circuit for said relay including a normal contact of the relay and a normal contact of said lever, a reverse circuit for said relay including a reverse contact of the relay and a reverse contact of the lever, means including a pole-changer operated by said switch for supplying said circuits with current of normal or reverse polarity, and an auxiliary circuit for said relay including said pole-changer and a back contact of the relay. 70
2. In combination a railway switch, a lever for the control of said switch, a polarized relay for the control of said lever, a source of current, a pole-changer connected with said source and operated by said switch, means for connecting said relay with said source through a normal contact on the lever and a normal contact on the relay or through a reverse contact on the lever and a reverse contact on the relay, and auxiliary means for connecting said relay with said pole-changer through a back contact on the relay. 75
3. In combination, a railway switch, a lever for the control of said switch, a polarized relay for the control of said lever, a pair of wires the first of which is connected with one terminal of said relay; means for connecting the second wire with the remaining terminal of said relay through a normal contact on the relay and a normal contact on said lever, or through a reverse contact on the relay and a reverse contact on the lever, or through a back contact on said relay; and means including a pole-changer operated by said switch for supplying current of normal or reverse polarity to said wires according as the switch is in normal or reverse position. 80
4. In combination, a railway switch, a lever for the control of said switch, a polarized relay for the control of said lever, a pair of wires the first of which is connected with one terminal of said relay; means for connecting the second wire with the remaining terminal of said relay through a normal contact on the relay and a normal contact on said lever, or through a reverse contact on the relay and a reverse contact on the lever, or through a back contact on said relay and a resistance the value of which is such as to permit either the normal or the reverse contact of the relay to close but to prevent the back contact from opening; and means including a pole-changer operated by said switch for supplying current of normal or reverse polarity to said wires according as the switch is in normal or reverse position. 85
5. In combination, a railway switch, a lever for the control of said switch, a polarized relay for the control of said lever, a source of current, a pole-changer operated by said switch, means operating when said switch is in either extreme position for energizing said relay in normal or reverse direction provided the neutral contacts of the relay are released, means for energizing said relay in the normal direction provided said pole-changer is in the normal position and the normal contacts of the relay are closed and said lever is in its normal to normal-indicating positions, and means for energizing said relay in the reverse direction provided said pole-changer is in the reverse position and the reverse contacts of the relay are closed and said lever is in its reverse to reverse-indicating positions. 90
6. In combination, a railway switch, means for the control of said switch, a relay, a normal and a reverse temporary circuit for said relay causing a partial functioning thereof, a normal and a reverse final circuit comprising contacts operated by said means and said switch to cause a complete functioning of said relay, and signals governing traffic over said switch and controlled by said relay. 95
7. In combination, a railway switch, a lever for the control of said switch, a polarized relay, a normal circuit for said relay including a normal contact of the relay and a normal contact of said lever, a reverse circuit for said relay including a reverse contact of the relay and a reverse contact of the lever, means including a pole-changer operated by said switch for supplying said circuits with current of normal or reverse polarity, an auxiliary circuit for said relay including said pole-changer and a back contact of the relay, and a signal governing traffic over said switch and controlled by said relay. 100
8. In combination, a railway switch, a lever for the control of said switch, a polarized relay, a source of current, a pole-changer connected with said source and operated by said switch, means for connecting said relay with said source through a normal contact on the lever and a normal contact on the relay or through a reverse contact on the lever and a reverse contact on the relay, auxiliary means for connecting said relay with said pole-changer through a back contact on the relay, and a signal governing traffic over said switch and controlled by said relay. 105
9. In combination, a railway switch, a lever for the control of said switch, a polarized relay, a pair of wires the first of which is connected with one terminal of said relay; means for connecting the second wire with the remaining terminal of said relay through a normal contact on the relay and a normal contact on said lever, or through a reverse contact on the relay and a reverse contact on the lever, or through a back contact on said relay and a pole-changer operated by said switch for supplying current of normal or reverse polarity to said wires according as the switch is in normal or reverse position. 110
10. In combination, a railway switch, a lever for the control of said switch, a polarized relay, a pair of wires the first of which is connected with one terminal of said relay; means for connecting the second wire with the remaining terminal of said relay through a normal contact on the relay and a normal contact on said lever, or through a reverse contact on the relay and a reverse contact on the lever, or through a back contact on said relay; means including a pole-changer operated by said switch for supplying current of normal or reverse polarity to said wires ac- 115

cording as the switch is in normal or reverse position, and a signal governing traffic over said switch and controlled by said relay.

10. In combination, a railway switch, a lever for the control of said switch, a polarized relay, a pair of wires the first of which is connected with one terminal of said relay; means for connecting the second wire with the remaining terminal of said relay through a normal contact on the relay and a normal contact on said lever, or through a reverse contact on the relay and a reverse contact on the lever, or through a back contact on said relay and a resistance the value of which is such as to permit either the normal or the reverse contact of the relay to close but to prevent the back contact from opening; means including a pole-changer operated by said switch for supplying current of normal or reverse polarity to said wires according as the switch is in normal or reverse position, and a signal governing traffic over said switch and controlled by said relay.

11. In combination, a railway switch, a lever for the control of said switch, a polarized relay, a source of current, a pole-changer operated by said switch, means operating when said switch is in either extreme position for energizing said relay in normal or reverse direction provided the neutral contacts of the relay are released, means for energizing said relay in the normal direction provided said pole-changer is in the normal position and the normal contacts of the relay are closed and said lever is in its normal to normal-indicating positions, means for energizing said relay in the reverse direction provided said pole-changer is in the reverse position and the reverse contacts of the relay are closed and said lever is in its reverse to reverse-indicating positions, and a signal governing traffic over said switch and controlled by said relay.

12. In combination, a railway switch, means for the control of said switch, a polarized relay, a circuit for said relay closed when the relay and said means are normal, a second circuit for said relay closed when the relay and said means are reversed, and a signal governing traffic over said switch and controlled by said relay.

13. In combination, a railway switch, means for the control of said switch, a relay, signals governing traffic over said switch and controlled by said relay, and a circuit for said relay including contacts operated by said means and said switch, as well as by said relay.

In testimony whereof I affix my signature.
66 HERBERT A. WALLACE.
